(57) **CLAIM**

The ornamental design for a remote control, as shown and described.

DESCRIPTION

FIG. 1 is a front plan view of the remote control, shown with the cover in the closed position.

FIG. 2 is the front plan view of the remote control of FIG. 1, shown with the cover in the open position.

FIG. 3 is the bottom plan view of the remote control of FIG. 1.

FIG. 4 is the back plan view of the remote control of FIG. 1.

FIG. 5 is the right side plan view the remote control of FIG. 1, the left side view being the same.

FIG. 6 is the right side plan view the remote control of FIG. 2 with the cover in the open position, the left side view being the same.

FIG. 7 is the top plan view of the remote control of FIG. 1.

FIG. 8 is a front left perspective view of the remote control of FIG. 1, with the cover shown in the closed position.

FIG. 9 is a front left perspective view of the remote control of FIG. 8, with the cover shown in the open position; and, FIG. 10 is a back right perspective view of the remote control of FIG. 1, with the cover shown in the closed position.

The broken lines in the drawings of the remote control are for illustrative purposes, and form no part of the claimed design.
